CIGAR MACHINE LOCKING MECHANISM

John F. Halstead, Brooklyn, N. Y., assignor to
International Cigar Machinery Company, a corporation of New Jersey

Application September 24, 1942; Serial No. 459,489

15 Claims. (Cl. 131—105)

This invention relates to cigar machines and more particularly to improved wrapper transfer mechanisms for transferring wrappers from a suitable source of supply, such for instance as a wrapper cutting device to a cigar bunch wrapping mechanism.

The present invention relates generally to a wrapper transfer device of the type disclosed in the patent to Wheeler, No. 2,235,857, and consists in an improvement thereon which enables the wrapper transfer to be more positively and accurately controlled.

The function of a cigar wrapper transfer is to receive and transfer a cut tobacco leaf wrapper from a source of supply to a wrapping device, and to properly guide it during its application to a cigar bunch being wrapped in said device. It is desirable to have the wrapper carrier remain absolutely stationary when it is positioned over the cutting platform to pick up a cut wrapper, and also when paste is being applied to one end of the wrapper and when the other end of the wrapper is being removed from the carrier by a tuck needle which presses it down upon the cigar bunch about which it is applied.

If the wrapper carrier is not maintained motionless over the wrapper cutting station, the cut wrapper raised by the elevating platform will be wrinkled, shifted and misplaced because any relative movement between the carrier and the cutting platform will interfere with the outspread form of the cut wrapper being transferred by suction from the latter to the former. If the carrier is not maintained motionless at the instant paste is being applied, the paste will be smeared over the wrapper and possibly applied on the wrong area thereof. The tuck needle also may be broken if the carrier is improperly positioned because of its striking against one side of the entrance to the needle groove in the carrier.

While Wheeler 2,235,857 constitutes a marked improvement over the prior art, it was found that where a continuous and circuitous cam track was employed to control the working movement of the wrapper carrier, there was a tendency for the wrapper carrier to have a certain amount of play when it was held momentarily over the aforementioned pickup and delivery stations, with the consequential deleterious effect on the wrapper and tuck needle just mentioned.

Skilled mechanics working on cigar machines were familiar with this problem for many years because it required much patience and skill on their part to properly locate the paste and tuck needle so they would be able to operate accurately

when the machine is run at full speed. It was found that while the paste and tuck needle would work satisfactorily when the machine was turned over by hand, they might be improperly located when the cigar machine was operated under power, especially when run at full speed.

The difficulty was due to the fact that the carrier had a certain amount of play or back lash at the two aforementioned stopping positions.

- 10. The problem of taking up this play without reducing the speed of the machine puzzled inventors and designers for many years. The reason for this was quite understandable, however, because if the machine is operated at the rate of say 13 cigars per minute, the carrier should remain absolutely stationary at each of the above-mentioned stations for approximately 205^{1/2} of a second. The problems due to inertia and momentum of the carrier and the operating mechanism therefore are believed to be self evident. Due to these facts, those skilled in the art contended with this problem the best they could by relying on a very high degree of accuracy in constructing this part of the cigar machine.
- 15. It is therefore an object of the present invention to provide a locking mechanism for the wrapper carrier which will be able to hold the wrapper carrier positively stationary when at the pickup and delivery stations without slowing down the speed of the machine.

Another object is to provide a device which will avoid the need for the high degree of accuracy heretofore considered necessary in the construction of the wrapper carrier and its associated mechanisms.

A further object is to provide an improved and simplified device for holding the wrapper carrier stationary when it is at the wrapper pickup and delivery stations.

- 20. An additional object is to provide a locking device for a wrapper carrier which travels in a closed circuitous path which will not interfere with the speed of operation of the cigar machine.

Another object is to provide a locking device which will be adjustable so that the same locking device can be used regardless of what shape cigar is being made by the cigar machine.

Another object is to provide a locking device for the wrapper carrier which will locate the carrier correctly at all critical positions and which will also prevent overtravel of the carrier.

With these and other objects, not specifically mentioned in view, the invention consists in certain combinations and constructions which will be hereinafter fully described, and then

specifically set forth in the claims hereunto appended.

In the accompanying drawings which form a part of this specification and in which like characters of reference indicate the same or like elements:

Fig. 1 is a side elevation partly in section, of the improved wrapper transfer;

Fig. 2 is a plan view of the same, with parts being broken away to expose further details of the device;

Fig. 3 is a partial side elevation illustrating the wrapper carrier locking device;

Fig. 4 is a bottom view of the lock controlling cam as seen from line 4—4 of Fig. 1.

Referring to Figs. 1 and 2, the improved wrapper transfer is supported on a hollow housing 10 attached to the baseplate of the cigar rolling machine and connected to its suction system, as in U. S. patents to Wheeler Nos. 2,215,490 and 2,235,857. In suitable bearings (not shown) formed in housing 10 is mounted a vertical shaft 11 which is continuously rotated by suitable bevel gears 12 and 13 from the drive shaft 14 of the cigar machine, in substantially the same manner as that shown in the above referred to patents. A horizontal arm 15, formed on housing 10, has suitable bearings (not shown), in which is journalled a vertical hollow shaft 100 in substantially the same manner as shown in the Wheeler Patent No. 2,235,857.

To the top of housing 10, and concentric with shaft 11, is fixed a cam 16 having in its upper surface a track 17. On suitable bushings (not shown) concentrically mounted with shaft 11, is loosely mounted a spur gear 18 meshing with a spur gear 19 fast on the aforementioned hollow shaft 100. On the upper face of spur gear 19 are mounted two suitable plates 20 and 21 having tapered holes 22 and 23 formed vertically therein which receive a tapered dowel pin 24, hereinafter described. Since there is no play for all practical purposes between gear 19 and wrapper carrier 62, the latter will be held positively motionless when the locking dowel pin 24 is in engagement with either of said tapered holes 22 and 23. The pin 24 and holes 22 and 23 are formed with tapers to facilitate the engagement thereof if they should not be exactly aligned when brought into locking engagement, and also because a taper automatically compensates for wear.

Gear 18 is driven by a gear 25 mounted on the hub of gear 18 and affixed to it by suitable pins (not shown). Gear 25 meshes with a gear segment 26 of a lever 27 which has a follower 28 in engagement with track 17 of cam 16. Therefore a gear 25 will be termed a driving gear and gear 18 will be called a driven gear. If desired, gears 18 and 25 may be formed integral one with the other. The lever 27 is pivoted on a stud 29 carried by an index disk or driving member 30 fast on the shaft 11, the stud passing through an arcuate slot 31a in gear 18 in order to permit relative motion between lever 27 and gear 18.

The function of lever 27 (or other suitable intermediate member) is to control the speed of gear 18 and thereby to drive gear 19 and the hollow shaft 100 on which gear 19 is mounted, at different speeds at different positions of wrapper carrier head 62 during each cycle of the machine. When the follower 28 moves in a concentric portion of cam track 17, as shown in dotted lines in Fig. 2, lever 27 is stationary with respect to gear 25, and the gear system 18,

25, 26 moves as one unit with disk 30, driving gear 19 at the same speed as gear 18. But when follower 28 engages with an eccentric portion or low or high part of track 17, the consequent turning of lever arm 27 causes the segment 26 to turn gear 25, thereby correspondingly advancing or retarding gear 18, as the case may be, with the result that the speed of gear 19 at that moment is increased or decreased, respectively, the speed varying in accordance with the curvature of track 17 at each point of the cycle.

At points where the reverse motion of segment 26 is equal in angular amplitude to the forward motion of disk 30, the gear 19 will not turn at all, and the hollow shaft 100 on which gear 18 is mounted will dwell. It is at these dwell positions that the tapered locking dowel pin 24 comes into action to hold gear 19 positively locked against all movement.

Tapered dowel pin 24 (Fig. 3) is mounted at one end of a lever arm 31 which is pivotally supported on a bracket 32. The other end of lever arm 31 carries a cam roller 34 which tracks against a dual cam constructed on the lower side of disk 30 (see Fig. 4). One part 33 of said dual cam is fixedly mounted on disk 30 while the other part 35 is adjustably mounted adjacent to cam 33 on screws 37 passing through elongated arcuate slots of part 35 and securing part 35 to disk 30. The cam roller 34 is pressed against the dual cam track 33, 35, by means of a compression spring 36 which is supported in suitable slotted openings on said bracket 32 and arm 31.

It is desirable to momentarily maintain the wrapper carrier head stationary at the pickup position and at the delivery station, for reasons already stated. When the wrapper carrier 62 is over the lifter head L, roller 34, due to the compression spring 36, will ascend into the cut-away portion 58 of cam 33, thus causing the dowel pin 24 to engage with hole 22 of plate 20 to lock gear 19 momentarily against all movement.

When wrapper carrier 62 has traveled to the wrapper applying station WA, roller 34 will have ascended into the cutaway portion 59 of cam 35, and in the manner just mentioned this would cause dowel pin 24 to descend into hole 23 of plate 21 which will have arrived at a position substantially in line with said pin to momentarily lock gear 19 against all movement. In cigar machines of the type referred to in the instant application, the aforementioned stopping intervals are exceptionally short, each averaging about .205 of a second, and the actual locking time at each stopping station is approximately .185 of a second.

A cigar machine of the type under discussion can be converted to wrap cigars of a wide variety of shapes. In wrapping cigars with different shapes, it is necessary to stop wrapper carrier 62 at different positions over the wrapper applying mechanism WA so that the wrapper will be fed correctly about the cigar bunch from wrapper carrier 62.

To make provision for this change-over, the present inventor has adjustably mounted cam 35 so that when cam 16 causes the wrapper carrier to come to a temporary pause at another fixed station, the cut away portion 58 can be turned to coact with roller 34 and thereby cause pin 24 to descend into hole 23 of plate 21 which has been similarly relocated.

To the lower end of the hollow shaft 100 on

which gear 19 is mounted, is clamped to hollow arm 38 which pivotally supports a hollow arm 39 held to arm 38 by a bolt 40. The free end of arm 39 forms a support for a vertical shaft 41 turning in a suitable bearing formed on said arm 39 and to which shaft the wrapper carrying head 62 is attached, which may be of a construction similar to that shown in U. S. Patent No. 2,292,361 issued to Carlson. From the free end of arm 39 projects a lateral extension 42 which carries a roller 43. To the upper end of shaft 41 extending from the free end of arm 39 is fastened a cam piece 44 carrying a roller 45 and having a slot 46 and a cam track 47. Rollers 43 and 45 engage with tracks 50 and 51 in the underside of the stationary cam 52 attached to horizontal arm 15, the roller 43 guiding shaft 41 in a predetermined path. Roller 45, in each position on this path, swings carrier head 62 to the proper angle for applying the cut wrapper to the particular cigar shape for which cam 52 is designed. The driving mechanism may be protected by a suitable cover (not shown) which may be similar to that shown in Wheeler, 2,235,857.

At proper points, cam 52 has projecting studs carrying rollers 53 and 54, with which engage slot 46 and track 47 of cam piece 44, thereby turning shaft 41 and reversing carrier head 62 after the same has delivered the wrapper at a conventional wrapper applying station WA and is returning to its receiving or pickup position. A more detailed description of the operation of cam 44 and the rollers coacting therewith is omitted for the sake of brevity; for such detailed description reference may be had to U. S. Patent No. 2,235,857 heretofore mentioned.

In the pickup position shown in Fig. 1, the carrier head 62 is locked in position in the manner hereinbefore mentioned over the lifter head L of the die, the cut wrapper being transferred from the latter to the former by a shift of the succession at the moment of contact. If there were any relative movement between the head 62 and the lifter platform L, the cut outspread wrapper would be misplaced and wrinkled, which in turn would cause the wrapper to be improperly applied about a cigar. Applicant made the present invention to eliminate this particular cause of trouble.

After wrapper carrier head 62 has delivered a wrapper to a cigar held in the wrapper applying device WA, cam tracks 50 and 51 coacting with rollers 43 and 45, respectively, guide carrier 62 toward stationary roller 53 so that slot 46 formed on cam piece 44 engages with stationary roller 53. When slot 46 engages with stationary roller 53, the swinging movement of carrier head 62 will be exclusively controlled by said slot and roller and also by roller 43 engaging with cam track 50. As carrier head 62 is thus swung into position over lifter head L, slot 47 starts to engage with stationary roller 54, as shown in Fig. 2. At this point there is a momentary pause in the movement of carrier head 62, and the locking device heretofore mentioned then comes into action to positively lock the driving mechanism for the carrier head during this momentary pause. After a cut wrapper has been picked up in the manner just described and the locking device has been unlocked, arm 39 imparts further movement to carrier 62 in order to cause the same to bring a cut wrapper to the wrapper applying mechanism WA. As carrier head 62 starts to travel toward wrapper applying station WA, slot 46 leaves stationary roller 53 and the swinging movement of carrier head 62 is then exclusively

controlled by slot 47 passing over stationary roller 54 and also by roller 43 engaging with stationary cam 50. When slot 47 is about to leave stationary roller 54, roller 45 coacting with cam track 51, and roller 43 coacting with stationary cam 50, then control exclusively the swinging movement of carrier head 62. As hereinbefore stated, for more detailed description of the same reference may be had to U. S. Patent No. 2,235,857 and patents referred to therein.

It will be seen, therefore, that in the movement of wrapper carrier head 62 between lifter head L and wrapper applying station WA, the movement of wrapper carrier head 62 must be interrupted cyclically, first when the head receives a wrapper from the source of supply, and secondly when the head carrying a wrapper is located above wrapper applying station WA, at which position paste is applied to the wrapper flag by means of a conventional paste applying bar 55 which is intermittently raised out of a suitable paste container 56 up against one end of the cut wrapper. After this operation a tuck needle 57, also of conventional design, enters groove 60 and removes the tuck end of the wrapper from carrier head 62 and presses it down upon the tuck end of a bunch located in wrapper applying station WA. The movement of the head is then restarted to properly feed the wrapper as it is being applied about the bunch, and the carrier head 62 subsequently moves back over wrapper cutting die L to receive a new wrapper therefrom. It is of utmost importance that carrier head 62 remain absolutely stationary when paste is being applied and when the tuck needle 57 is operating, because if said head is not stationary, paste may be applied at the wrong part of the wrapper and the tuck needle may miss slot 60 and strike the side thereof, which will result in breakage.

By providing a locking mechanism for the driving mechanism of the wrapper carrier which comes into operation at these positions, the inventor has avoided the above possibilities of damage both to the machine and the cigar.

The wrapper applying mechanism WA may be of a construction similar to that shown in the U. S. patent issued to J. P. Durning, No. 2,290,171. The tuck needle 57 and operating mechanism thereon may be similar to that shown and described in U. S. patent to Clausen, No. 2,281,095. For further illustration of a suitable grid type of paster, reference may be had to the U. S. patent to Shadlock, No. 863,106.

The invention above described may be varied in construction within the scope of the claims, for the particular device selected to illustrate the invention is but one of many concrete embodiments of the same. The invention therefore is not to be restricted to the precise details of the structure shown and described.

What is claimed is:

1. In a cigar machine provided with a source of supply of wrappers and a bunch rolling station, a wrapper transfer device, including a suction carrier head, a movable support for said head, means for intermittently moving said head in a closed and irregularly curved path to and from said source of supply and bunch rolling station once in each cycle of said machine, including a vertical shaft journaled in the machine; a driving member secured to said shaft; speed advancing and retarding means mounted on said driving member for controlling the speed of movement of said head; means associated with said driving member for engaging and

locking said support against movement at at least one of the predetermined positions of said head at said source of wrapper supply and said bunch rolling station in said closed and irregularly curved path, and stationary cams cooperating with said driving member for effecting the movement of said head along said path.

2. In a cigar machine, a wrapper transfer comprising: a wrapper carrier head, means for moving said head in a closed circuitous path between a source of wrapper supply and a wrapping station said means including a rotatable support on which said carrier head is pivotally mounted, and a device adapted to engage said support for positively locking said support against movement while the carrier head is at the source of supply and at the wrapping station, said device including a detent, a member rigidly connected to said support and provided with a plurality of recesses suitably spaced to be respectively moved into positions opposite said detent when said carrier head is at the wrapper supply and wrapping stations, and instrumentalities for displacing said detent into engagement with said recesses.

3. In a cigar machine, a wrapper transfer mechanism comprising: a wrapper carrier head, means for moving said head in a closed path between a source of supply of wrappers and a wrapping station, including a vertical support, a shaft journalled in said support, a fixed cam, a driving and a driven gear mounted on said shaft, a driving member fixed to said shaft and provided with a vertical stud, a gear segment secured to said stud and meshing with said driving gear, a cam follower secured to said segment engaging in a track of said fixed cam, a horizontal arm formed on said support, a shaft journalled in said arm, a gear mounted on said last-mentioned shaft for coacting with said driven gear, a locking device constructed and arranged to be actuated by said driving member for locking the gear mounted on said last-mentioned shaft against all movement during predetermined portions of the wrapper transferring cycle, said wrapper carrier head being mounted on said last-mentioned shaft for movement therewith.

4. In a cigar machine, a wrapper transfer mechanism comprising: a wrapper carrier head; means for moving said head in a closed path between a source of supply of wrappers and a wrapping station, including a vertical support; a shaft journalled in said support; a fixed cam; a driving and a driven gear mounted on said shaft; a driving member fixed to said shaft and provided with a vertical stud; a gear segment secured to said stud and meshing with said driving gear; a cam follower secured to said segment engaging in a track of said fixed cam; a horizontal arm formed on said support; a shaft journalled in said arm; a gear mounted on said last-mentioned shaft for coacting with said driven gear; a spring tensioned lever arm constructed and arranged to be actuated by a cam mounted on said driving member; a tapered locking pin connected to said lever arm; tapered holes formed on the gear mounted on said last-mentioned shaft for receiving said pin at predetermined intervals to positively lock said last-named gear against all movement; said wrapper carrier head being mounted on said last-mentioned shaft for movement therewith.

5. In a cigar machine, a wrapper transfer mechanism comprising: a wrapper carrier head; means for moving said head in a closed path between a source of supply of wrappers and a wrap-

ping station, including a vertical support; a shaft journalled in said support; a fixed cam coaxial with said shaft; a bracket fixedly connected to said cam; a cam actuated lever arm pivotally connected to said bracket; a latch connected to said lever arm; a driving and a driven gear mounted on said shaft; a driving member fixed to said shaft and provided with a vertical stud; a cam for actuating said lever arm mounted on said driving member; a gear segment secured to said stud and cooperating with said driving gear; a cam follower secured to said segment engaging in a track of said fixed cam; a horizontal arm formed on said support; a shaft journalled in said horizontal arm; a gear mounted on said second-named shaft coacting with said driven gear; means mounted on the gear on said second named shaft constructed and arranged to coact with said latch to lock the gear on said second named shaft during predetermined periods of its cyclical travel; a fixed cam coaxial with said second-named shaft; articulated members secured to said second-named shaft and mounting said head for movement thereabout; and a cam follower mounted on one of said members for cooperation with said second-named cam for controlling the path of movement of said head.

6. In a cigar machine wrapper transfer, the combination with a suction wrapper carrier head, of means for moving said head to and from a source of supply, said means comprising a pair of vertical shafts, one of said shafts driving the other shaft, means on said driving shaft for driving the other shaft at a varying rate of speed and thereby effecting the movement of said head, including a driving member affixed to said driving shaft, a stationary cam associated with said driving shaft, a gear loosely mounted on said driving shaft, a lever provided with a gear segment pivotally mounted on said driving member, said segment engaging with said gear, a gear fixed to said driven shaft and meshing with said loose gear for carrying the drive to said driven shaft, a cam follower on said lever arranged to track in said cam for controlling the rate of speed of said driven shaft, a stationary locking device for temporarily locking said driven shaft in position at predetermined periods of its rotary travel, and means forming a part of said locking device constructed and arranged to receive actuating movement from said driving shaft to lock against movement and unlock for free movement said driven shaft at said predetermined periods.

7. In a cigar machine wrapper transfer, the combination with a suction wrapper carrier head, of means for moving said head at varying rates of speed to and from a source of supply of wrappers once each cycle of said machine, said means comprising a driven and a drive shaft, a driving member on said drive shaft, a speed change device mounted on said member, a cam cooperating with said device for controlling the rate of speed of said driven shaft, a stationary bracket mounted on said cam, a spring tensioned lever arm mounted on said bracket, a cam follower mounted on one end of said arm for engagement with a cam driven by said drive shaft, and a locking device constructed and arranged on the other end of said lever arm for locking said driven shaft in predetermined positions at predetermined periods of its rotary cycle.

8. In a cigar machine, the combination with a wrapper carrier head, and means for mounting said head for movement in a closed path, of a drive for moving said means and thereby mov-

ing said head in said closed path, mechanism for controlling the movement of said drive, said mechanism including a vertical shaft, a stationary cam coaxial with said shaft, a driven gear loosely mounted on said shaft, a driving gear mounted on a hub of said gear and pinned thereto, said driven gear being provided with an arcuate slot, a driving member fixed to said shaft for rotation therewith, a stud mounted in said member and projecting through said slot, a lever provided with a gear segment at one end pivoted on said stud, said segment engaging said driving gear, a cam follower on the other end of said lever, said follower engaging a track in said cam for controlling the motion of said head during the rotation of said shaft, a bracket fixed to a stationary support on the cigar machine, a lever arm having a cam follower at one end pivotally mounted on said bracket, a locking mechanism formed on the other end of said lever arm for engaging with said drive to maintain said means stationary, a second cam fixed to said driving member, and tension means for holding said cam follower in engagement with said second cam.

9. Driving mechanism for a cigar machine wrapper transfer comprising a vertical support, a shaft journaled in said support, a stationary cam, a driving member secured to said shaft, connected driving and driven gears mounted on said shaft, a stud located in said member and provided with a gear segment lever, said segment engaging one of said gears to rotate the same relative to said shaft, a horizontal arm forming a part of said support, a hollow shaft journaled in said arm, a gear fixed to said hollow shaft and meshing with said driven gear on said first-named shaft, a stationary cam located about said hollow shaft, a locking device mounted on a fixed part of the cigar machine, a cam mounted on said driving member for actuating said locking device to engage with the gear on said hollow shaft to lock the same against movement, a wrapper carrier head, an articulated support for said carrier head fixed to said hollow shaft, a cam follower mounted on said articulated support and engaging a track in said second-named stationary cam, and a movable cam mounted on said articulated support and arranged to engage rollers on said second stationary cam to reset the position of said carrier head at the termination of a wrapper feeding cycle.

10. In a cigar machine, a cut cigar wrapper transfer mechanism comprising, a wrapper carrier head for transferring cut wrappers from a supply station to a wrapper applying station, a drive for moving said carrier head between said two stations and stopping said carrier head momentarily over at least one of said stations in each cycle of the machine, and a locking device for momentarily locking said drive each time said carrier head is momentarily stopped over one of said stations, said drive including a rotatable support on which said carrier head is pivotally mounted, and said device including a detent adapted to engage said support when the carrier head is stopped at one of said stations and thereby prevent movement of said support, and mechanism for operating said detent in each machine cycle, said mechanism being adjustable to operate said detent sooner or later in each cycle.

11. In a cigar machine, a cut cigar wrapper transfer mechanism comprising, a wrapper carrier head for transferring cut wrappers from a supply station to a wrapper applying station, a drive for moving said carrier head between said

two stations and stopping said carrier head momentarily over each of said stations, a cam actuated locking device for momentarily locking said drive each time said carrier head is momentarily stopped over each of said stations, and cam mechanism for operating said locking device, said cam mechanism being adjustable to operate said locking device at various points in the transfer cycle.

10 12. In a cigar machine provided with a source of supply of wrappers and a bunch rolling station, the combination with a wrapper transfer device including a suction carrier head and a movable support for said head, of means for moving said head at varying speeds at different positions of said head, to and from said source of supply and bunch rolling station once in each cycle of said machine, said means operating to stop said head momentarily at positions adjacent the source of supply and bunch rolling station, and a device for locking said support against movement while said carrier head is at the source of supply and at the bunch rolling station.

15 13. In a cigar machine provided with a source of supply of wrappers and a bunch rolling station, the combination with a wrapper transfer device including a suction carrier head and a movable support for said head, of mechanism for moving said support and head at varying speeds at different positions of said head in a closed and irregularly curved path to and from said source of supply and bunch rolling station once in each cycle of said machine, said mechanism operating to stop said head momentarily at positions adjacent the source of supply and bunch rolling station, a device for locking said support against movement while at the source of supply and at the bunch rolling station, and said mechanism including means for guiding the movement of said head in its closed irregularly shaped path, said guiding means including a closed continuous cam track, an arm connected to said support, and a cam roller on said arm engaging said track.

20 14. In a cigar machine, a wrapper transfer comprising a wrapper carrier head, drive means for moving said carrier head between a source of supply of cut wrappers and a wrapping station and momentarily stopping said head at said wrapping station in each cycle of the machine, and locking means for preventing movement of said carrier head when stopped at said wrapping station, said drive means including a rotatable support on which said carrier head is pivotally mounted, and said locking means including a detent adapted to engage said support when said head is at said wrapping station and thereby prevent movement of said support at said station in each machine cycle, and mechanism for operating said detent in each machine cycle, said mechanism being adjustable to operate said detent sooner or later in each cycle.

25 15. In a cigar machine wrapper transfer drive, an intermittently driven hollow shaft, a hollow arm mounted on said hollow shaft, a suction wrapper carrier head, a hollow arm on which said carrier head is supported, the arm supporting said head being articulated on the arm supported on said hollow shaft, a driven member fixed to said hollow shaft, means for driving said driven member at various speeds at various positions of said head, said driving means operating to stop said hollow shaft at two predetermined positions corresponding to the wrap-

per receiving and wrapper depositing positions of said carrier head, latch receiving means formed on said driven member, latch means engaging said latch receiving means at said predetermined stationary positions of said hollow shaft to lock said driven member in said stationary predetermined positions, means for releasing said latch

means, and mechanism for guiding the movement of said head through a closed and irregularly curved path as the carrier head is moved by the rotation of said hollow shaft.

JOHN F. HALSTEAD.
